G. F. KNOX

COMPRESSOR PISTON

Filed Jan. 10, 1922

FIG. 1

FIG. 2

INVENTOR.
BY George F. Knox.
Morsell & Keeney.
ATTORNEYS.

UNITED STATES PATENT OFFICE.

GEORGE F. KNOX, OF MILWAUKEE, WISCONSIN, ASSIGNOR TO KNOX REFRIGERATION CO., OF MILWAUKEE, WISCONSIN, A CORPORATION OF WISCONSIN.

COMPRESSOR PISTON.

Application filed January 10, 1922. Serial No. 528,353.

This invention relates to improvements in valve structures for compressors or the like.

One of the objects of the invention is to provide a valve structure of such construction that the valves have a very small amount of movement relative to their seats, consequently, reducing wear of the valves to a minimum, and which permits the structure to be operated at a relatively high speed with 10 a minimum amount of noise.

A further object of the invention is to provide a valve structure of such construction that the parts thereof may be easily and conveniently assembled, removed and replaced 15 in case the parts become worn, corroded, or eaten away by the gases to such an extent as to require replacing.

A more specific object of the invention is to provide a novel valve structure in which 20 the cylinder head, which may be either of the fixed or yieldable type, is provided with one or more annular laterally extending flanges to form a seat for an annular flat valve, the cylinder head also being provided with an 25 annular depending flange terminating over the valve to limit upward movement thereof.

Another and more specific object of the invention is to provide a novel check valve in the piston head, the piston on its working 30 side being provided with an annular recess which is adapted to receive an annular depending flange carried by the check valve, means being provided also to limit movement of the check valve relative to the piston head.

35 A further object of the invention is to provide a two-part piston head of such construction that one part constitutes a valve normally rigid in relation to the other part, but which will yield should the piston encounter an obstruction on its return stroke, for example, an accumulation of water.

The invention consists in the novel constructions, arrangements and devices to be hereinafter described and claimed for carrying out the above stated objects and such other objects as will appear from the following description of a certain preferred embodiment illustrated in the accompanying drawings, wherein—

50 Fig. 1 is a vertical sectional view of a fragmentary portion of a compressor, embodying the principles of the invention; and

Fig. 2 is a sectional view taken on the line 2—2 of Fig. 1.

Like characters of reference designate like parts in both views.

Referring to the drawings, it will be seen that the invention is illustrated as embodied in a compressor having a piston, designated generally by the reference character 5, working in a cylinder 6 provided with a head 7, the head 7 preferably being of the yieldable type and normally held against the annular shoulder 8 of the cylinder by a relatively stiff spring 9.

In the preferred form of the invention, the cylinder head includes a bottom portion 10 provided with an annular outwardly extending flange portion 11, the portion 10 being secured to the cylinder head by a threaded stud 12. The cylinder head also is provided with an annular vertically positioned ring 13, the upper side of which is positioned against the under side of the cylinder head, the ring being secured thereto by a plurality of screws 14. The ring 13 is provided with a plurality of apertures 15 for the passage of the gases being compressed and with an inwardly extending portion 16 which is concentric with and spaced from the portion 11, the portions 11 and 16 forming a seat for an annular flat floating valve 17. Circumferential movement of the valve 17 relative to its seat is prevented by a pin 18 which extends through an aperture in the valve 17 and into the seat portion 11. Upward movement of the valve 17 relative to its seat is limited by a depending annular flange 19 formed on the cylinder head and terminating over the valve 17. In order to retard or cushion the closing of the valve 17, a plurality of recesses 20 are provided in the under side of the flange 19, these recesses acting as dashpots, as will readily be apparent.

The piston 5 comprises a lower portion 5^a rigidly secured on the piston stem 21 by a nut 22 and an upper portion 5^b mounted on the upper end of the stem and which is provided with an annular recess 23 in which is positioned a relatively stiff spring 24, the stem carrying a nut 25 adapted to bear on said spring to hold the portion 5^b normally against a seat 26 formed on the stem. The part 5^a is provided with a tapered seat 27 for

the annular valve 28 formed on the part 5^b. A plurality of vertically extending grooves 29 are formed in the periphery of the part 5^b to provide for a freer passage of the gases between the parts 5^a and 5^b.

The portion 5^b of the piston is provided on its working side with an annular recess 30, the lower portion being provided with a plurality of passageways 31 so that the gases 10 to be compressed may freely pass upwardly through the head. An annular flat check valve 32 is positioned over the recess 30 and is provided with an annular depending flange portion 33 which extends into said recess. 15 The flange 33 bears against an annular perforated ring 34 carried by the part 5^b thereby preventing relative lateral movement of the valve 32 on its seat. The portion 33 is provided with an outwardly laterally extending 20 flange 35 adapted to bear against the under side of the ring 34 to limit upward movement of the valve 32 relative to its seat. The ring 34 is adjustable, being locked in the desired position by a set screw 36, whereby the 25 amount of travel of the valve 32 may be regulated, as desired.

It will be apparent from the foregoing description that the movement of the valves 17 and 32 need only be very slight, consequently 30 the wear of the valves and their seats is reduced to a minimum. The valve structure may be operated at a relatively high speed with practically no noise because of the small amount of travel of the valves. Ordinarily 35 there is no movement of the part 5^b of the piston relative to the part 5^a. Should the piston encounter water or the like in the bottom of the cylinder on its return stroke the part 5^b will yield, that is to say, move upwardly relative to the part 5^a and permit the trapped fluid to escape between the valve 28

and its seat 27 thus relieving the valve 32 and its associated parts of any undue strain.

I claim:

1. A piston having an annular recess 45 formed in its working side, passageways extending from the opposite side of said piston into said recess, a check valve comprising an annular flat portion adapted to be positioned over said recess, an annular flange portion 50 depending into said recess from said flat portion, and an annular ring carried by the piston and co-operating with said depending flange portion for the purpose described.

2. A piston having an annular recess 55 formed in its working side, passageways extending from the opposite side of said piston into said recess, a check valve comprising an annular flat portion adapted to be positioned over said recess, an annular flange portion 60 depending into said recess from said flat portion, an annular adjustable ring carried by the piston and co-operating with said depending flange portion, and means to prevent movement of said ring relative to said 65 piston.

3. A piston having an annular recess formed in its working side, passageways extending from the opposite side of said piston into said recess, a check valve comprising an annular flat portion adapted to be positioned over said recess, a flange formed centrally of said annular flat portion, and extending into said recess, a laterally extending flange formed on the free end of said 70 first mentioned flange, and adjustable means 75 cooperating with said laterally extending flange to limit upward movement of said valve.

In testimony whereof, I affix my signature.

GEORGE F. KNOX.
